UNITED STATES PATENT OFFICE.

CHARLES NEWTON, OF BUFFALO, NEW YORK.

PROJECTILE.

1,172,035.

Specification of Letters Patent. Patented Feb. 15, 1916.

Application filed March 22, 1915. Serial No. 16,013.

To all whom it may concern:

Be it known that I, CHARLES NEWTON, a citizen of the United States, residing at Buffalo, in the county of Erie and State of New York, have invented new and useful Improvements in Projectiles, of which the following is a specification.

My invention relates to rifle bullets or projectiles for game shooting and has for its object the production of a bullet for this purpose which will penetrate the atmosphere during flight without undue loss of energy through air resistance and which will expand easily upon impact with the game thus giving good killing power, yet shall not expand unduly when striking thick flesh or bone, thus insuring good penetration through the thicker heavier portions of the body of the game struck.

In the accompanying drawings: Figure 1 is a longitudinal sectional elevation of one form of bullet or projectile embodying my invention. Fig. 2 is a front elevation of the same. Fig. 3 is a longitudinal sectional elevation of the inner jacket section. Fig. 4 is a cross section in line 4—4, Fig. 1. Fig. 5 is a longitudinal sectional elevation showing a modification of my invention. Fig. 6 is a cross section thereof taken on line 6—6, Fig. 5. Fig. 7 is a longitudinal sectional elevation of the inner jacket section shown in Figs. 5 and 6.

Similar characters of reference indicate corresponding parts throughout the several views.

It is known to those skilled in the art that game when shot is struck by the bullets at various portions of their anatomy, the point of impact not always being under the absolute control of the shooter, due to errors in the aim; also that the different portions of the animal which may be struck vary in their density and consequent resistance to the bullet. The bullet should therefore be so formed that if the softer portions of the game only are struck the bullet will expand sufficiently to produce a paralyzing wound, yet, it should not expand so freely that when the denser portions are reached it will break up so rapidly as to result in a superficial wound without sufficient penetration to reach a vital spot.

Bullets, as at present made, if sufficiently yielding to expand freely upon striking soft parts, are apt to break up and lack in penetration when the denser, tougher parts

are encountered. Conversely, if made sufficiently strong to insure proper penetration when striking the denser parts, they do not expand sufficiently when the softer parts only are struck. Therefore the requirement is for a bullet which will expand sufficiently upon striking the softer portions and yet have its expansion so limited that it will penetrate the denser portions.

It is likewise known to those skilled in the art that when a soft point bullet expands the forward portion of the jacket opens outward and turns back over and along the sides of the rear portion of the bullet, continuing this process, if of sufficient power and meeting with sufficient resistance, until the jacket of the bullet is turned inside out and the leaden core freed from it, whereupon the core usually goes in pieces and penetration soon stops. To overcome this difficulty I have designed a bullet which will expand freely to a certain extent, after which expansion practically ceases and the bullet continues its course as a solid projectile with a blunt point, usually surrounded with jagged portions of the ruptured forward portion of the jacket.

Referring to Figs. 1—4, 1 represents an inner jacket section of tough, strong and ductile material, such as copper, steel or the like, this section having a tubular body, the front part 2 of which is of somewhat smaller diameter than the rear part 3 thereof, and has its front end closed by a transverse head 4 while its rear end is open but provided with an inwardly projecting annular flange 5. Within this inner jacket section is arranged a rear core section 6 of lead or other plastic or malleable material.

Around the inner jacket section is arranged an outer jacket section 7 of tough strong and ductile material such as copper, steel or the like, the outer section having a tubular body which is of greater length than the inner jacket section and which has its rear part constructed of cylindrical form and its front part constructed of forwardly tapering form. The rear end of the outer jacket is closed by a transverse head 8 while its front end is open. The inner jacket section containing the rear core section is arranged in the rear part of the outer jacket section and bears with its flanged rear end against the rear head of the outer jacket section, as shown in Fig. 1. When thus assembled an annular

channel is formed between the reduced front part of the inner jacket section and the adjacent part of the bore of the outer jacket section which channel opens forwardly into the interior of the front part of the outer jacket section. Into this channel is placed a filling 10 of molten solder which upon hardening forms a ring or band which securely connects the front end of the inner jacket section and the adjacent central part of the outer jacket section.

Within the front part of the outer jacket section is arranged a front core section 11 of lead or other soft, plastic or malleable material, the front core section abutting at its rear end against the front end of the inner jacket section while the front end of the front core section preferably projects forwardly through the open front end of the outer jacket section and preferably terminates in a sharp point or tip 12. After the parts of the bullet are thus assembled the same are swaged into the shape shown in Fig. 1 or any other desired contour.

In use, when the bullet strikes the game the exposed tip of soft material, expands and ruptures the front end of the outer jacket section, thus forming a large and irregularly shaped point which tears and lacerates the tissues with which it comes into contact. This expansion and rupturing continues, as the bullet progresses, until it reaches the forward end of the rear core section and inner jacket section. The front end of the rear core section being protected by the solid front end of the inner jacket section does not expand materially and the rear core section is thus held together by the inner jacket section and completes the penetration until it emerges on the opposite side of the object struck or is brought to rest by the resistance. Meanwhile the outer jacket section has been folded back over the rear portions of the bullet and its irregularities contribute to the laceration of tissues and shock imparted. By connecting the front end of the inner jacket section with the outer jacket section any tendency to strip the outer jacket entirely off the inner section is prevented and the mushrooming effect of the front part of the bullet is practically arrested at the front end of the inner jacket section. By this method soft lead may be used for the forward core section and the bullet may be permitted to expand with the greatest freedom until a degree of expansion is reached sufficient to insure proper shocking power in case only soft parts of the game be struck, yet in case denser portions are struck the rear core section inclosed in the inner jacket section will be protected from disintegration or undue expansion and insure proper penetration to reach the vitals of the game which is hit.

The composition of the front core section is preferably, though not necessarily, somewhat softer than that of the rear core section of harder material so that the front core section will mushroom or deform more readily upon striking a surface when fired from a firearm and leave the rear core section practically intact so that the latter can fully enter or penetrate the harder parts of the object struck by the bullet.

While it is preferable to connect the front end of the inner jacket section by soldering or otherwise with the outer jacket section the main advantages of my invention are obtained even though the inner and outer jacket sections are not connected in this manner. For instance, as shown in Figs. 5, 6 and 7, the tubular body 13 of the inner jacket section is not separated at its front end from the adjacent part of the outer jacket section by an intervening annular channel which is filled with solder, but instead these parts engage each other evenly throughout their opposing surface and the tenacity of the inner jacket section is relied upon to limit the mushrooming effect of the front core section and the outer jacket section at the front end of the inner jacket section, and leave the latter solid and in a condition to penetrate farther into the object hit by the bullet.

I claim as my invention:

1. A projectile comprising an inner jacket section which is closed at its front end, a rear core section arranged within the inner jacket section, an outer jacket section inclosing the inner jacket section and projecting forwardly beyond the latter, and a front core section arranged within the front part of the outer jacket section.

2. A projectile comprising an inner jacket section which is closed at its front end, a rear core section arranged within the inner jacket section, an outer jacket section inclosing the inner jacket section and projecting forwardly beyond the latter, and a front core section arranged within the front part of the outer jacket section, said rear core section being of harder material than said front core section.

3. A projectile comprising an inner jacket which is closed at its front end and open at its rear end, a rear core section arranged on said inner jacket section, an outer jacket section inclosing said inner jacket section and having a closed rear end and an open front end and having its front part projecting forwardly beyond the front end of said inner jacket section, and a front core section arranged in the outer jacket section in front of the inner jacket and rear core section.

4. A projectile comprising an inner jacket section which is closed at its front end, a rear core section arranged within the inner

jacket section, an outer jacket section inclosing the inner jacket section and projecting forwardly beyond the latter, and a front core section arranged within the front part of 5 the outer jacket section, said inner and outer jacket sections being connected at the front end of the inner jacket section.

5. A projectile comprising an inner tubular jacket which is closed at its front end 10 and open at its rear end and which has the front part of its tubular wall constructed of smaller diameter than the rear part thereof, a rear core section arranged in the inner jacket section, an outer tubular jacket sec-

tion having its rear part inclosing said 15 inner jacket section and its front part projecting forwardly beyond said inner jacket section and forming an annular channel between the reduced front part of said inner jacket section and the bore of said 20 outer jacket section, a filling of adhesive material arranged in said channel and connecting the adjacent parts of the inner and outer jacket sections, and a front core section arranged in the front part of the outer jacket 25 section.

CHARLES NEWTON.
